UNITED STATES PATENT OFFICE.

JOSHUA V. VAN NAME, OF MARINERS HARBOR, NEW YORK.

RIFLE-GRIP.

1,277,002.

Specification of Letters Patent. Patented Aug. 27, 1918.

Application filed September 28, 1917. Serial No. 192,760.

To all whom it may concern:

Be it known that I, JOSHUA V. VAN NAME, citizen of the United States, residing at Mariners Harbor, in the county of Richmond and State of New York, have invented certain new and useful Improvements in Rifle - Grips, of which the following is a specification.

This invention has for its principal object 10 the production of a device which is adapted to be attached to the stock of a rifle for facilitating the gripping thereof.

Another object of this invention is the production of an adjustable rifle grip which 15 is adjustably mounted upon the stock of the rifle thereby permitting the same to be moved to accommodate the gripping thereof by persons having arms of different lengths.

Another object of this invention is the 20 production of a rifle grip which has a plurality of sockets formed therein, whereby the thumb and fingers of the user may fit therein for facilitating the holding of the grip and at the same time preventing injury 25 to the hands of the user.

A still further object of this invention is the production of a rifle grip wherein the grip is formed from a sheet of material so 30 as to be comparatively inexpensive in construction, although it is provided with sockets for facilitating the gripping thereof, thus preventing the user from drawing the sight of the rifle out of correct alinement with the target.

35 With these and other objects in view, this invention consists of certain novel combinations, constructions, and arrangement of parts, as will be hereinafter fully described and claimed.

40 In the accompanying drawing I have illustrated one form of my invention, wherein,

Figure 1 is a side elevation of the rifle grip applied to the arm.

Fig. 2 is a central transverse section 45 through a rifle showing the rifle grip in end elevation, and

Fig. 3 is a detail perspective view of the rifle grip.

Referring more specifically to the accompanying drawing, it will be seen by referring particularly to Fig. 3 that the rifle grip is formed from a blank sheet of material and comprising a body 1. This body 1 is bent to

form a substantially U-shaped structure in cross section, while the inwardly extending flanges 2 are formed upon the edges of the body 1. These flanges 2 are spaced apart as is clearly shown in Figs. 2 and 3 to provide sufficient space in the positioning of the rifle grip upon a rifle.

The rifle upon which this device is used is disclosed in general by the numeral 3 and is provided with a stock 4. This stock 4 has an elongated slot 5, formed therein for purposes to be hereinafter specified. The rifle grip is positioned upon the stock 4 so as to permit the flanges 2 thereof to bear upon the upper surface of the stock 4 as shown in Fig. 2. For this reason it is obvious that the stock will sufficiently support the grip, although the grip may be moved along the stock in either direction to accommodate the user of the device. A retaining bolt 6 passes through the opening 7 formed in the body 1 and also projects through the slot 5 formed in the stock 4. The winged nut 8 is screwed onto the projecting end of bolt 6 and in this way holds the bolt in set position. It is obvious that by shifting the winged nut, the body of the grip will be slightly loosened from its clamping in movement with the stock 4 and at this time this grip may be moved to a desired position on the stock 4. The nut may then be tightened upon the bolt thus holding the body 1 in a binding engagement with the stock 4, whereby the grip is adjusted to accommodate the length of the arm of the particular user at this time.

The body 1 is provided upon one side with the elongated thumb socket 9, while extending substantially around the portion of the body are formed a plurality of finger sockets 10. These sockets are formed by striking the sheet metal body 1 inwardly for a slight distance whereby each socket will be provided with a continuous shoulder 11 there around as clearly shown in Fig. 3. It will also be seen that the inner walls of these sockets may be roughened or slit as indicated at 12 for constituting a suction grip for the thumb and fingers of the user's hand.

When this device is in use, it is mounted in a set position upon the stock of the gun, as above specified. It will accommodate the length of the arm of the user and at this time the thumb of the left hand of the user

will fit within the thumb sockets 9 while the tips of the fingers will fit within the sockets 10. It is of course obvious that the hand of the user will be firmly engaging the grip, 5 although by having the thumb and fingers fitting within the sockets any possibility of the user's hand slipping upon the grip is prevented. Furthermore by having the shoulders formed within the socket the comparatively broad bearing socket is provided 10 against which the thumb and fingers of the user's hand will bear for assisting in holding the grip from slipping, although it will be impossible for the socket to injure the user's 15 hand when the gun is firing. Furthermore the formation of the roughened element within the sockets will also aid the user in holding the grip from slipping.

It is a well known fact that very often the 20 sights of a gun are pulled out of alignment with the target, when the trigger is pulled. If however a grip is provided so as to enable the operator to firmly hold the grip as he becomes very tense at this time and naturally 25 grips firmly the rifle, he can very easily hold the rifle against movement and thus increase the accuracy of the shot. Therefore, the present device will enable the operator to firmly hold the rifle against movement while 30 the socket formed in the body of the rifle grip will facilitate the gripping of this device. Furthermore since the rifle grip is formed from sheet metal it is very light and will not constitute a burden when in use 35 owing to an increased weight upon the rifle, while it may easily be adjusted to accommodate the user.

Since the rifle grip is stamped from a blank sheet of material it may be very easily 40 constructed, since the sockets formed therein may be struck at the same time the grip is struck from a blank, while the flanges may also be folded at this time.

From the foregoing description it will be 45 seen that a very efficient rifle grip has been produced which will facilitate the holding of a rifle very steady when in operation.

It is of course obvious that many changes 50 may be made in the detail construction of this rifle grip such for instance as the arrangement of the sockets, without departing from the spirit of the present invention, and for this reason it is not intended to limit the rifle grip to the specific form herein 55 shown, as it is desired to include all such forms of the rifle grip as properly come within the scope of the claims.

What I claim is:

1. A rifle grip comprising a body, said 60 body having an elongated socket formed therein, said body also having a plurality of independent reduced sockets formed therein, said sockets having continuous abutment shoulders, whereby said body may be firmly

gripped by the fitting of the user's thumb 65 and fingers within said sockets, and means for releasably retaining said body upon the stock of a rifle.

2. A rifle grip comprising a body, said body being formed from a blank and being 70 bent to comprise a substantially U-shaped structure in cross section, inwardly projecting flanges formed on the edges of said body, said body having a plurality of sockets formed therein, said sockets having continuous 75 shoulders formed therearound, whereby said shoulders will facilitate the holding of the body, said sockets having roughened inner portions, a bolt connecting the side portions of said body and a nut carried by said 80 bolt.

3. In a device of the class described, the combination of a rifle stock having a slot formed therein, a rifle grip comprising a body, said body having flanges formed 85 thereon, said body fitting upon said stock and said flanges gripping said stock thereby positively supporting said grip upon said stock, a bolt passing through said body and through said slot, means carried by said bolt 90 for clamping said body upon said stock whereby said grip will be retained upon said stock in an adjusted set position, and sockets formed in said body whereby said grip may be firmly held.

4. In a device of the class described, the combination of a rifle stock having a slot formed therein, a rifle grip comprising a body, a bolt passing through said body and said slot, means carried by said bolt for 100 clamping said body upon said stock, thus causing said grip to be retained upon said stock in an adjusted set position.

5. In a device of the class described, the combination of a rifle stock having a slot 105 formed therein, a rifle grip comprising a body, said body having flanges formed thereon, said body fitting upon said stock and said flanges gripping said stock for supporting said grip upon the stock, a bolt passing through said body and through said slot, means carried by said bolt for clamping said body upon said stock, thus retaining said grip in an adjusted position upon said stock.

6. In a device of the class described, the combination of a rifle stock having a slot formed therein, a rifle grip comprising a body having flanges formed thereon, said body fitting upon said stock and said flanges gripping said stock for supporting said grip 115 upon said stock, means carried by said body and passing through said slot for retaining the same in an adjusted set position, and sockets formed in said body for facilitating the holding of said grip.

7. In a device of the class described, the combination of a rifle stock having a slot formed therein, a rifle grip comprising a

body, said body fitting upon said stock, means carried by said body and projecting through said slot for retaining said body in an adjusted set position upon said stock, and 5 sockets formed in said body for facilitating the holding of the grip.

In testimony whereof I affix my signature in presence of two witnesses.

JOSHUA V. VAN NAME.
